UNITED STATES PATENT OFFICE.

GEORGE F. McCHEY, OF PROVIDENCE, RHODE ISLAND, ASSIGNOR TO J-M-BRAIDER CO., OF PROVIDENCE, RHODE ISLAND, A CORPORATION OF RHODE ISLAND.

CARRIER FOR BRAIDING MACHINES.

Application filed January 27, 1926. Serial No. 84,063.

This invention relates to carriers for braiding machines; and has for its object to provide in such a carrier an improved arrangement of yarn take-up mechanism including 5 an arm or lever fulcrumed at one end adjacent the yarn package and arranged to lift the package from a stop to control the letting off of the yarn.

A further object of this invention is the 10 provision of a fixed stop latch to engage the teeth of the yarn package and a lever arm arranged to be operated by the thread tension to lift the package clear of the stop to let off the yarn.

15 With these and other objects in view, the invention consists of certain novel features of construction, as will be more fully described, and particularly pointed out in the appended claims.

20 In the accompanying drawings:

Figure 1 is a side elevation partly in section showing the yarn package as resting upon the fixed stop latch, in which position it is releasably retained against rotation.

25 Figure 2 is a side elevation showing the lifting lever arm in section and positioned to lift the yarn package clear of the stop latch to permit rotation of the yarn package.

Figure 3 is a section taken on line 3—3 30 of Figure 1, looking in the direction of the arrows.

Figure 4 is a sectional edge view of the lever arm.

Figure 5 is an end view of the lever arm 35 sectioned on line 5—5 of Fig. 4, illustrating the downwardly-extending stop latch engaging guide lips.

It is found in the practical operation of 40 so-called high speed braiding carriers of this character, of advantage to provide a relatively long let off control arm so as to render the action of the arm let off mechanism less sensitive than is the case where a shorter leverage is employed.

45 It is also found of advantage to provide a stop latch which is fixed to the carrier frame to arrest rotation of the yarn package and to so arrange this lever arm as to be operated by a movement of the yarn tensioning mechanism to lift the yarn package clear 50 of this latch permitting it to rotate and let off more yarn; and the following is a detailed description of my invention and showing one construction and arrangement of parts

by which these advantageous results may be 55 accomplished:—

With reference to the drawings, 10 designates the base of the carrier, which supports the thread package spindle 11 and the weight standard 12 on which latter the usual yarn 60 take up weight 13 slides.

On this base is fixed a stop latch 14 which extends upward from the body thereof into position to engage the teeth 15 of the spool portion 16 of the yarn package 17. This 65 package may be arranged as is herein shown to be supported on the upper end of the stop latch 14 and in order to provide simple and effective means for lifting this package clear 70 of the stop, I have provided a lever arm 18 which has an opening 19 at one end to set over the spindle 11 and rest upon the collar or saddle 20 beneath the center of the package 17, and this arm or lever is also provided 75 with an opening 21 to loosely fit over and be guided on the stop latch 14; guiding ears or lips 22 being also formed on this lever to assist in the guiding action of the arm to prevent it from being disengaged from the stop when drawn up to an unusual height 80 by action of the let off mechanism. The free end 23 of this lever 18 is herein shown as being provided with a connecting wire 24, the upper end 25 of which is looped around the weight standard 12 and in position to 85 be engaged by the weight 13 when carried upwardly by tensioning of the yarn 26 and when such upward movement of the weight is sufficient it serves to lift the lever arm 18 and cause its middle portion 27 which is intermediate its fulcrumed end and the end 90 23 where power is applied, to engage the under surface of the yarn package to lift its teeth 15 clear of the latch permitting the package to rotate under tension of the yarn 95 to release more yarn and when released to drop again presenting another tooth to be engaged by the stop latch 14 and so to intermittently repeat this operation as more yarn is required during the braiding operation.

100 By this construction, it will be seen that the fulcrum point of the lift arm or lever, is beneath the center of the thread package and its opposite or free end is connected to be operated through movement of the yarn 105 take up weight and the portion intermediate its opposite ends is arranged to engage the under side of the yarn package to lift the

same free from the stop to release more yarn.

In some cases, it is found of advantage to provide a pair of spaced, downwardly-projecting fingers 28 to engage the opposite sides of the base to prevent the constant side motion of the hardened lever 18 from cutting into the softer spindle 11, the stop latch 14 which extends through opening 21 in the lever also cooperates to prevent the engagement of the lever with the other sides of the spindle.

My improved device is very simple and practical in construction and is effective in its operation and by its use a carrier may 15 be run at a high speed and still nicely control the let off of the yarn.

The foregoing description is directed solely towards the construction illustrated, but I desire it to be understood that I reserve 20 the privilege of resorting to all the mechanical changes to which the device is susceptible, the invention being defined and limited only by the terms of the appended claims.

25 I claim:

1. A braider carrier comprising a base for supporting a thread package, a stop for the package fixed relative to the base, and means for lifting the package clear of its stop to 30 let off more yarn.

2. A braider carrier comprising a base for supporting a thread package, a stop for the package fixed relative to the base, and means operated by the tensioning of the yarn for 35 lifting the package clear of its stop to let off more yarn.

3. A braider carrier comprising a base for supporting a thread package, a stop for the package fixed relative to the base, a lever 40 located beneath the package, and means whereby the tensioning of the yarn is caused to move said lever to lift the package from engagement with said stop to let off more yarn.

45 4. A braider carrier comprising a base for supporting a thread package, a stop fixed relative to the base, teeth on the package arranged to engage said stop, a lever fulcrumed at one end and connected at its 50 opposite end to be operated by thread tension and having an intermediate portion arranged to lift the package from said stop.

55 5. A braider carrier comprising a base for supporting a thread package, a stop fixed relative to the frame, teeth on the package arranged to engage said stop, a thread tension weight, a lever guided on said stop fulcrumed at one end and connected at its 60 opposite end to be operated by the movement

of said weight and having an intermediate 60 portion arranged to lift the package from engagement with said stop.

6. A braider carrier comprising a base, a package carrying spindle on the frame, a stop for the package fixed relative to the 65 base, a lever fulcrumed at one end adjacent said spindle, and connected at its opposite end to be operated by thread tension and having an intermediate portion arranged to act upon and release the package from said 70 stop.

7. A braider carrier comprising a base for supporting a thread package, a package stop fixed on the frame on which the package normally rests, and means operated by the 75 tension of the yarn for lifting the package clear of the stop to let off more thread.

8. A braider carrier comprising a base having a yarn package spindle, a fixed stop for the package, a lever fulcrumed at one end 80 on the spindle, its opposite end being positioned to be connected to be operated by thread tension and having an intermediate portion guided on said stop and arranged to act upon to release the package from said 85 stop.

9. A braider carrier comprising a base having a yarn package spindle, a fixed stop for the package, a lever having openings and 90 adapted to be positioned over said spindle and stop to be fulcrumed on the spindle and guided by the stop and having its free end connected to be operated by the thread tension to lift the package clear of the stop.

10. A braider carrier comprising a base having a yarn package spindle, a fixed stop for the package, a lever having openings and 100 adapted to be positioned over said spindle and stop to be fulcrumed on the spindle and guided by the stop and having its free end connected to be operated by the thread tension to lift the package clear of the stop, and guiding means including said stop for preventing said lever from engaging said spindle.

11. A braider carrier comprising a base, a yarn package spindle thereon, a weight guide on said base at one side of the spindle, a stop on the base, a lever having a portion 110 engaging said package between said spindle and weight guide to lift the same clear of the stop, said lever being fulcrumed at a point spaced from the spindle and on the opposite side of the spindle from the weight guide.

In testimony whereof I affix my signature.

GEORGE F. McCACHEY.
